2,495,005

METHOD OF AND APPARATUS FOR
MAKING SOAP CAKES

Irving M. Hoglin, Denver, Colo.

Application April 2, 1945, Serial No. 586,241

16 Claims. (Cl. 25—8)

1

This invention relates to the making of soap cakes and more particularly to a method and apparatus for making a cake of soap having embodied therein indicia of a contrasting color, such as a letter, symbol, monogram, trade-mark, etc., which extends completely through the cake.

One of the objects of the invention is to provide an improved method of making a cake of soap of the kind referred to.

Another object is to produce a cake of soap embodying contrasting colors by causing different colored soap materials to be first properly formed by opposed complementary dies and then caused to become interfitting by relative movement.

Yet another object is to produce an improved method of making soap cakes which will result in the automatic continuous production of individual cakes of soap having embodied therein indicia of contrasting color extending completely through the cake.

A further object of this invention is to produce improved apparatus for carrying out the improved method which apparatus will be fully automatic.

A still further object is to produce improved apparatus which will form from complementary dies streams of soap material of contrasting color, cause an interfitting of said streams of soap by simultaneous equal movements in opposite directions, and then automatically cut said interfitting soap material from the streams at the proper time interval to form individual soap cakes.

Yet a further object is to produce a soap cake making machine which will continuously form and interfit oppositely moving streams of soap material of contrasting color and then automatically cut the interfitting material when the extent of interfitting is such as to equal the desired thickness of a cake of soap.

A further object is to produce improved means for cutting a stream of soap being extruded from a die to thereby form individual pieces of soap.

Other objects of the invention will become apparent from the following description taken in connection with the accompanying drawings in which:

Figure 1 is a top view of a soap making machine embodying my invention whereby indicia embodied in cakes of soap can be produced by my improved method of manufacture;

Figure 2 is a front view of the machine shown in Figure 1;

Figure 3 is an enlarged front view showing the relationship between the extruding dies and the knives and knock-out paddle of the cutting mechanism;

2

Figure 4 is a sectional view taken on the line 4—4 of Figure 3 showing the die construction for making the main body of the cake of soap;

Figure 5 is a sectional view taken on the line 5—5 of Figure 3 showing the die construction for making the contrasting colored indicia in the cake of soap;

Figure 6 is a sectional view taken on the line 6—6 of Figure 1 showing the cutting mechanism ready to make a cut;

Figure 7 is a top view of the cutting mechanism;

Figure 7A is an enlarged top view of part of the cutting mechanism showing details of construction;

Figure 8 is a sectional view taken on the line 8—8 of Figure 7 showing details of construction;

Figure 9 is a schematic view showing the control means for the motor which operates the cutting mechanism; and

Figure 10 is a schematic view showing a modified control means for the cutting mechanism.

Referring to the drawings in detail, the improved apparatus shown for carrying out my improved method of soap cake manufacture has a frame 1 upon the opposite ends of which are mounted electric motors 2 and 3 which are of the variable speed type, the varying of the speeds of the motors being under the control of suitable levers 4 and 5 on the exterior of leg compartments 6 and 7 at opposite ends of the frame. On the frame adjacent the motor 2 is mounted a casing 8 having a cylindrical bore 8' in which is a screw 9 driven by said motor 2. There is also shown a hopper 10 whereby soap material in suitable form may be fed into the cylinder of the casing and forced out its forward end by rotation of the screw 9. In a similar manner there is associated with the motor 3 a casing 11 provided with a cylindrical bore 11' having mounted therein a screw 12 which is driven by the motor 3. There is also provided a hopper 13 for feeding soap material to the cylinder to be forced out its forward end by the screw 12. Soap material can be fed 45 to the hoppers in any suitable manner, as by means of conduits. The cylinder 8' and the screw therein are arranged to handle a soap material for the body portion of the finished cake of soap, whereas the cylinder 11' and the screw 12 are arranged to handle a soap material for the indicia which is to be embodied in the main body of the soap cake, said soap material to be of contrasting color with respect to the cake body. As an example of the contrasting colors, the soap 55 body may be made of white soap material and the

indicia may be made of green colored soap material. The particular indicia which is illustrated as being embodied in the soap cake is the letter "O," but it is to be understood that other letters, monograms, emblems, words, trade-marks, etc., may be embodied in the cake of soap in a color which is contrasting to the color of the body of said cake.

The casings 8 and 11 are aligned and in spaced relation with the forward ends of the cylinder in each casing opposed to each other. On the forward end of the casing 8 at the open end of its cylinder, there is mounted an extruding die indicated by the letter "B" and on the forward end of the casing 11 there is an extruding die "I." These dies are bolted to the ends of the casings by suitable stud bolts 14 so that they may be readily removed and replaced by other dies when different indicia is to be embodied in the cake or the general outline of the cake changed, as for example, from a rectangular shape to a round shape.

The dies "B" and "I" are shown in detail in Figures 3, 4 and 5 and reference is now made to these figures. The die "B," from which the main body of soap is to be made, has a rectangular shaped channel 15 therethrough and is employed to make a rectangular shaped soap cake body. The channel 15 at the rear end communicates with the cylinder 8' and its forward end opens toward the die "I." The forward end of the channel is smaller than the rear end and the walls of the channel converge from the rear end toward the forward end so that the soap material which is forced through the die will be compressed before it is extruded from the forward open end of the die. Compressing, of course, will be brought about by the action of the screw 9 continuously forcing soap material into and through the channel 15. Centrally positioned within the channel is a hollow cylindrical member 16 provided with a desired wall thickness and being longitudinally arranged in the channel. This cylinder is supported in the central part of the channel by spokes 17 which are relatively thin so that they will not obstruct flow of the soap material and readily permit the soap to flow around the spokes and become united under the compressing action before the soap is extruded from the open forward end of the die. The cylindrical member 16 extends to the forward open end of the die and it is by means of this cylindrical member that an aperture in the stream of soap being extruded will be made which is annular in cross section. When the material of contrasting color is received in this annular aperture the letter "O" will result which is the letter being used as an illustration in the particular embodiment shown. With the die "B" arranged, as shown, it is seen that the stream of soap material being extruded from the forward open end of the die will have a square outer perimeter and an annular aperture extending in a longitudinal direction.

The die "I" is formed to be complementary to the die "B." This die "I" is therefore shaped to form a hollow cylindrical stream of soap which is of such cross section that it can fit into the annular aperture in the stream of soap being extruded through the die "B." To make the cylindrical stream of soap, the die is formed with a channel 18 of circular cross section, the rear end of which communicates with the cylinder in the casing 11 and the forward open end thereof being opposite the end of the cylindrical member

16 of the die "B." The diameter of the channel 18 at its forward open end is slightly less than the external diameter of the cylindrical member 16 in the die "B" and the axis of the open end of the channel 18 is so positioned as to coincide with the axis of the cylindrical member 16 of die "B." The rear end of the channel 18 is flared so as to readily receive the soap material from the cylinder 11' and to also compress the soap material as it is forced into the channel by the screw 12. Within the channel 18 is a solid cylindrical member 19 which is held therein by spokes 20. The axis of this cylindrical member coincides with the axis of the channel and the external diameter of the cylindrical member at the forward open end of the channel is slightly larger than the diameter of the hollow cylindrical member 16 in the die "B." Thus it is seen that as the soap is extruded through the channel 18 it will come out of the die in the form of a cylindrical tube and will be of such size as to fit within the annular aperture of the stream of soap material coming from the die "B." The rear end of the solid cylindrical member 19 tapers to a substantial point at the rear end of the channel 18, thus aiding in compressing soap material in the channel as the material is forced therein by the screw 12.

The open ends of the complementary dies "B" and "I" are spaced apart a distance which is slightly greater than the thickness of the soap cake which is to be produced. In making the soap cake the motors 2 and 3 are driven at such speeds that the rate at which each stream of soap is being extruded through the complementary dies will be substantially equal. This permits the soap streams to be extruded from the dies at the same time and the ends of the streams to reach the center of the space between the die at substantially the same time after which the streams will become interfitted. As there is continuous movement of the streams in opposite directions, the interfitting will continue until the end of each stream approaches the die opposite the die from which it is extruded. At this time the interfitting portions of the two streams of soap can be severed from the streams and thus produce a cake of soap which has embodied therein and extending completely therethrough an indicia of a color contrasting to that of the cake body. Although the soap material being extruded is plastic in form, the streams will nevertheless interfit readily since the unsupported portions of the streams, before interfitting takes place, are so short that there will be no harmful sagging of the streams prior to interfitting. The cake of soap being made will probably not be thicker than an inch and a half, thus it is seen the greatest unsupported length of extruded soap will not be greater than approximately three-fourths of an inch.

Although I prefer to cause the streams of soap being extruded to move simultaneously from the dies at the same rate of speed, it is possible to first cause one stream to be extruded and then the other stream to be extruded, provided, of course, the thickness of the soap cake to be formed and the soap material is such that no such sagging will take place that the two streams cannot be caused to readily interfit. Such a procedure in obtaining interfitting of the two streams is within the scope of my invention.

The mechanism for cutting the streams to form the soap cake will now be described and reference is made to Figures 1, 6, 7 and 9. The

frame 1, on its rear side, has mounted thereon a shaft 21 by means of a suitable supporting bracket 22. This shaft is arranged to have its axis parallel with the coinciding axes of the two dies "B" and "I." Keyed to this shaft are spaced collars 23 and 24 from which extend integral cutting blades 25 and 26, similar to a knife blade, being beveled at one edge to provide a sharp cutting edge. These blades are so spaced apart and so related to the dies that when the shaft 21 is rotated the blade 25 will pass along the forward face of the die "B" and the blade 26 will pass along the face of the die "I," thereby performing cutting of the two streams of material being extruded by the dies. The cutting of each stream will occur at the face surface of the die.

The shaft 21 is arranged to be driven by suitable gearing 27 from a motor shaft 28 of an electric motor 29. As shown in the schematic view of Figure 9 this motor shaft 28 has associated therewith a brake 30 which is normally held applied by a spring 31 and released by a solenoid or magnet "S." Associated with the line 32 leading to the motor 29 is a timer, a main switch for the motor and also a switch for the solenoid "S" of the brake which is connected to the line by conductors 33. The timer and the two switches are all enclosed in a single box generally indicated by the letter "T." The timer at periodic intervals will cause a closing of the main circuit of the motor and a simultaneous closing of the circuit for the solenoid. Thus the brake 30 will be released and the motor started. Starting of the motor will swing the cutting blades 25 and 26 through one revolution and these blades will cut the two streams of soap material being extruded by the dies. The timer is so arranged that it will cause a breaking of the circuit to motor 29 and to the solenoid of the brake when the motor has rotated the blades through the one revolution. There will then be a re-application of the brake and the stopping of the motor at the proper time. The timer switch is so coordinated with the speed of the extruded streams of soap material that the blades will be operated when the end of each stream of extruded material substantially reaches the opposed die, this condition being illustrated in Figure 3. Under such circumstances each blade will only be required to cut one stream, the blade 25 cutting the stream from the die "B" and the blade 26 cutting the stream from the die "I." The end surface of the die adjacent the tops thereof are beveled so that the blades, when rotated, will be guided to move along the end surfaces of the dies so as to make a clean shearing cut.

It is possible that when the interfitted portions of the streams are cut from the streams by the blades, the cake of soap will not freely "drop out" from the streams by gravity. In order to insure that this will be done, there is associated with the blades a "kick-out" paddle 34. This paddle extends from a collar 35 loosely mounted on the shaft 21 between the blade collars 23 and 24. The blade collars are provided with lugs 36 which fit into slots 37 in the collar 35. The slots 37 are of considerably greater arcuate length than the lugs to thus provide a lost motion arrangement between the blades and the paddle. A hair pin type of spring 38 is connected between each lug 36 and the paddle collar 35, as best shown in Figures 8 and 9. These springs bias the paddle so that it will be normally in substantially the same plane as the blades (see Figure 8), yet will permit the blades to move relatively to the paddle

by a compressing of the hair pin springs. By this arrangement, when the blades are operated to perform a cutting operation, the paddle will be moved along with the blades to where it engages the top surface of the interfitted portions of the streams where it will remain while the blades move relatively thereto and cut the streams. This action is illustrated in Figure 7. The arcuate slots and the lugs on the collars 23, 24 and 35 are so related that the yieldable lost motion will not be taken up until the blades pass completely through the streams. At this time the lugs will be at the opposite ends of the slots and therefore will pick up and positively rotate the paddle with the shaft 21. This positive rotation will insure that the paddle will "kick out" the cake of soap and when so "kicked out" it will fall down into the chute 39. From here the soap bar can be conveyed to a suitable finishing machine whereby the cut soap cake can be pressed into its final form, having the desired curved edges, etc. After the cutting has been performed and the paddle has "kicked out" the soap cake, the hairpin springs 38 will function to again bring the paddle into substantially the same plane as the blades, as indicated in Figure 3.

From the foregoing description it will be apparent that with the apparatus described, soap cakes can be continuously made that have embodied therein indicia of a contrasting color which extends completely through the cake. The soap material of contrasting colors will be fed to the hoppers and cylinders and this material will then be extruded through the complementary dies "B" and "I." The dies will so form the streams of soap that they can become interfitted as the streams move in opposite directions and when the interfitted portions are of a proper length they will be cut off from the streams to form the soap cake with the indicia embodied therein. The cutting of the interfitted portions will be very rapid and thus it will not be necessary to stop the streams of soap during the cutting operation. The cutters will be periodically operated and the operation is coordinated with the rate of movement of the extruded streams of soap material, both of which move at the same rate of speed. By employing complementary dies and interfitting the streams of soap material moving in opposite directions, there will be formed clear cut indicia in the soap cake. It will be noted that all the compressing of the soap material takes place prior to the streams of soap material becoming interfitted so as to place the soap material forming the indicia into the main body. Thus this indicia will not be acted upon by any pressures which tend to deform the sharp outline thereof. The result will be a soap cake having an attractive indicia.

In Figure 10 I have shown a schematic arrangement of apparatus whereby the operation of the cutting blades can be directly controlled by the extruded soap. This is accomplished by means of a photo-electric beam which is broken by one of the streams at the proper time. When this beam is broken a timer will be set in operation and the switches of the cutter mechanism will operate.

As shown in Figure 10, there is provided photo-electric tubes 39 and 40 on opposite sides of the dies and so positioned with respect to the stream of soap being extruded from the die "B" that this beam will be broken when the end of the stream is at a point where it is about to engage the surface of the complementary die "I." These tubes are connected in circuit with the box "T" con-

taining the timer and the switches. When the beam between the photo-electric tubes is broken the timer will close the switches so that the brake will be released and the blades given one rotation to perform the cutting operation. When this one rotation is accomplished the timer will permit the opening of the switches, thereby reapplying the brake and stopping the motor. When the interfitted portions of the streams of material have been severed and "kicked out" the beam will no longer be broken and thus the cycle will be set up for the next cutting operation.

Being aware of the possibility of modifications in the particular apparatus disclosed, together with the disclosed steps of the method of manufacturing a soap cake and also the possibility of employing the apparatus and method for making articles from plastic materials other than soap, I do not intend that my invention be limited in any manner except in accordance with the appended claims.

What is claimed is:

1. The method of producing an article from plastic material of contrasting colors so that said article will comprise a body of one color of material having embodied therein and extending completely therethrough, material of another color, said method comprising the extruding in opposite directions of separate streams of the contrasting colored plastic material from opposed spaced complementary dies so positioned that the streams become interfitted in the space between the dies by relative movement in opposite directions while said streams project from the dies and then cutting interfitted portions from the streams.

2. The method of producing an article from plastic material of contrasting colors so that said article will comprise a body of one color of material having embodied therein and extending completely therethrough, material of another color, said method comprising the simultaneous extruding at the same rate of speed of separate streams of the contrasting colored plastic material from opposed spaced complementary dies so positioned that the streams can become interfitted during movement in opposite directions in the space between the dies.

3. The method of producing an article from plastic material of contrasting colors so that said article will comprise a body of one color of material having embodied therein and extending completely therethrough material of another color, said method comprising the simultaneous extruding at the same rate of speed of streams of the contrasting colored plastic material from opposed spaced complementary dies so positioned that the streams can become interfitted during movement in opposite directions in the space between the dies, and cutting interfitted portions from the streams at periodic intervals.

4. The method of producing cakes of soap having embodied therein indicia of contrasting color extending completely through the cake comprising simultaneous forming by opposed spaced complementary dies separate streams of soap material of contrasting color with one stream having a longitudinally extending aperture therein of a cross section conforming with the outline of the indicia desired and the other of a cross sectional contour to fit the aperture, causing said streams to move simultaneously at equal rates of speed in opposite directions and assume an interfitting relation during said movement, and simultaneously cutting the streams when the end of each stream

approaches the die from which the other is being extruded.

5. In apparatus of the class described two complementary dies positioned in opposed spaced relation, means for extruding a stream of plastic material through each die and into interfitting relation with the other stream in the space between the dies, and means for simultaneously cutting streams adjacent the surfaces at the outer open ends of the dies after portions of the streams have become interfitted to an extent substantially the distance between the dies.

15 6. In apparatus of the class described two complementary dies positioned in opposed spaced relation, means for extruding a stream of plastic material through each die and into interfitting relation with the other stream in the space between the dies, and means for simultaneously cutting the streams adjacent the interfitted portions.

20 7. In apparatus of the class described two complementary dies positioned in opposed spaced relation, means for extruding a stream of plastic material through each die and into interfitting relation with the other stream in the space between the dies, and means for simultaneously cutting the streams adjacent the interfitted portions, and means for positively moving the interfitted portions from the stream after the streams have been cut.

25 8. In apparatus of the class described two complementary dies positioned in opposed spaced relation, means for extruding a stream of plastic material through each die and into interfitting relation with the other stream in the space between the dies, a means for simultaneously cutting the streams at points adjacent the interfitted portions and comprising two blades, an electric motor for operating the blades, a normally applied brake for the motor and means for starting the motor and releasing the brake.

30 9. In apparatus of the class described, two complementary dies positioned in opposed spaced relation, means for extruding a stream of plastic material through each die at equal rates of speed and into interfitting relation in the space between the dies, and mechanism for cutting each stream adjacent its die at a time when the streams have become interfitted over a distance substantially equal to the distance between the dies.

35 10. In apparatus of the class described, two complementary dies positioned in opposed spaced relation so that materials coming therefrom move in opposite directions, means comprising a screw for extruding a stream of plastic material through each die and into interfitting relation in the space between the dies, means for driving said screws so that the rate of extrusion of the material from each die is equal, a cutter for severing each stream adjacent its die, and means for simultaneously operating the cutters.

40 11. In apparatus of the class described, two complementary dies positioned in opposed spaced relation so that materials coming therefrom move in opposite directions, means for extruding streams of plastic material through each die at equal rates of speeds and into interfitting relation in the space between the dies and mechanism including two cutting blades for simultaneously cutting the streams adjacent the dies and means for periodically operating the cutting blades.

45 12. In apparatus of the class described, complementary dies, means for extruding plastic material through the dies into interfitting relation, a shaft adjacent the dies, means for rotating the shaft, cutting blades secured to the shaft and

when moved through an arc by the shaft being capable of severing the plastic materials coming from the dies, and a member rotatable with the shaft after the blades have cut the material and arranged to engage a surface of the material between the dies.

13. In apparatus of the class described, complementary dies, means for extruding plastic material through the dies into interfitting relation, a shaft adjacent the die, means for rotating the shaft, cutting blades secured to the shaft and when moved through an arc by the shaft being capable of severing the plastic materials coming from the dies, a member mounted on the shaft and arranged to engage the surface of material between the dies, a lost motion connection between the member and the shaft, a yieldable connection between the member and the shaft and normally biasing the member to the limit of the lost motion connection and to a position in substantially the same plane as the blades whereby during cutting by the blades the member can engage the surface of the material and the blades move relatively thereto by a yielding of the yieldable connection, together with the lost motion connection, and then pick up the member for simultaneous movement when the materials have been severed.

14. In apparatus of the class described, complementary dies in opposed spaced relation, means for extruding plastic material through the dies and into interfitting relation, and cutting mechanism for the material comprising two simultaneously rotatable cutting blades, said blades being spaced apart and each arranged to cut material adjacent a die after being extruded, a member arranged to engage material between the blades and move it out of the streams of extruded material after the blades have severed such from the said streams, and means for rotating the blades and the member.

15. In apparatus of the class described, complementary dies in opposed spaced relation, means for extruding plastic material through the dies and into interfitting relation, and cutting mechanism for the material comprising two simul-

taneously rotatable cutting blades, said blades being spaced apart and each arranged to cut material adjacent a die after being extruded, a member arranged between the blades and normally lying in substantially the same plane thereof, driving means for the blades and connecting means between the member and driving means including a yieldable lost motion means for permitting the blades to move relatively to the member and cut the material while the member engages the material between the blades and then to positively move the member so as to move the severed material.

16. In apparatus of the class described, two complementary dies positioned in opposed spaced relation, so that materials coming therefrom move in opposite directions, means for extruding a stream of plastic material through each die at equal rates of speed and into interfitting relation in the space between the dies, mechanism for simultaneously cutting each stream adjacent its die, and means controlled by one of the streams when its end has reached a predetermined distance from its die for causing operation of the cutting mechanism.
